(57) **CLAIM**

The ornamental design for a tack removal implement, as shown and described.

DESCRIPTION

FIG. 1 is a perspective top front right view of a tack removal implement, showing my new design;
FIG. 2 is a front elevation view thereof, wherein a rear elevation view is an identical image thereof;
FIG. 3 is a right side elevation view thereof, wherein a left side elevation view is an identical image thereof;
FIG. 4 is a top plan view thereof; and,
FIG. 5 is a bottom plan view thereof.
